UNITED STATES PATENT OFFICE.

THOMAS C. DONAHUE, OF PITTSBURGH, PENNSYLVANIA, ASSIGNOR OF ONE-HALF TO
WALTER L. JOHNSON, OF MCKEESPORT, PENNSYLVANIA.

SHARPENING MACHINE FOR REAMERS AND THE LIKE.

Application filed March 1, 1923. Serial No. 622,058.

To all whom it may concern:

Be it known that I, THOMAS C. DONAHUE, a citizen of the United States, residing at Pittsburgh, in the county of Allegheny and State of Pennsylvania, have invented certain new and useful Improvements in Sharpening Machines for Reamers and the like, of which the following is a specification.

This invention relates to sharpening machines and more particularly to hand operated sharpening machines for reamers, milling cutters and the like tools.

One of the principal objects is to provide a hand operated sharpening machine in which the angle of operation of the sharpening means may be suitably adjusted. Another object is to produce a machine of this character in which the movements of the workman's hands are guided to give the proper angle of stroke to the sharpening tool. A further object is to provide a machine which is adapted to sharpen reamers or milling cutters of various diameters and lengths. Still another object of this invention is to provide means for substantially micrometric adjustment of the so-called clearance or relief of the cutting edges of said reamers or milling cutters. Still a further object is to provide a machine wherein sharpening means of various sizes may be used and quickly installed. Additional objects and features of this invention will appear from the following description taken in connection with the accompanying drawings.

In the drawings:

Fig. 1 is a top plan view of my complete sharpening machine in working condition. Fig. 2 is a side elevation of the complete machine, corresponding to Fig. 1.

Fig. 3 is an enlarged view of the sharpening means showing the method of mounting it as well as its adjustable guide-support.

Fig. 4 is an end elevation of the complete machine, corresponding especially to Fig. 2.

Fig. 5 is a cross-sectional view of the adjustable clamp for the sharpening means.

Fig. 6 is an end view corresponding to Fig. 5.

Fig. 7 is a fragmentary view showing

the end of a guide-rod used in my machine.

Fig. 8 is an end-view corresponding to Fig. 7.

Fig. 9 is an end-view of an adjustable support used in my machine.

Figs. 10, 11 and 12 are diagrammatic views showing the method of final adjustment of the cutting edges of a reamer or milling-cutter.

Referring to the drawings, my sharpening machine comprises a table 1 having legs 2 of suitable height, a head-stock 3 and a tail-stock 4. Intermediate these stocks, and secured on one side of the table is an arm 5, the top of which is preferably made level with the top of table 1. The head-stock is furnished with a fixed center 6 secured therein by a set-screw 7. The tail-stock is provided with a threaded spindle 8 having at the inner end the center 9 and at the outer end the hand-wheel 10, whereby the center 9 may be moved in or out, to accommodate various lengths of reamers or milling-cutters. In the figures the invention has been shown as applied to an adjustable reamer 11, for which purpose the machine is mostly used. Both stocks are longitudinally movable on the table and are held in the desired positions by means of the stud-bolts 12 and 13, engaging slots 14 and 15 in table 1, and by the wing-nuts 16.

Upon the arm 5 is slidably mounted a standard 17 held thereon by the large headed guide-screw 18 screwed partly in the base of the standard and having an enlarged portion 19 which snugly fits into a finished slot 20 cut in said arm. This standard can be moved back and forth by means of the feed-screw 21 which is threaded into an upwardly directed lug 22 situated at the end of the arm 5 and preferably cast integral therewith. This feed-screw is secured for rotation to the standard in any desired manner, for instance by means of a pin 23, driven into the circular boss 24 on the standard, and engaging a groove 25 cut in the smooth end 26 of the feed-screw.

Mounted centrally of the standard and vertically adjustable therein by means of a set-screw 27 is the adjustable rest 28 having the cylindrical body portion 29 and a head 30. This head has a drilled aperture 31, a saw-cut slot 32, a threaded stud 33 and a wing-

nut 34, by means of which a rest-bar 35 may be supported and clamped in any desired position.

The rest-bar is substantially L-shaped and carries at the end of its long and horizontal leg 36 a push-blade 37 made of resilient material and secured therein by the rivets 38. The shorter and vertical leg 39 of the rest-bar terminates with a slightly reduced portion 40 in which a groove 41 has been cut. Upon this portion is mounted for rotation in a horizontal plane the swivel-guide 42 comprising a head 43 and a shank portion 44. The latter is partly drilled vertically to receive the reduced portion 40 to which it is secured against escape by means of a set-screw 45 engaging the aforementioned groove 41.

In the head 43 of the swivel-guide is drilled the horizontal aperture 46 which is slidably engaged by a guide-rod 47 of suitable length, having at its forward end a downwardly directed and flattened head 48, preferably provided with inwardly pointing prongs 49.

The sharpening means, such as a file, or the carborundum slab 50 is secured to the underside of the guide-rod 47 by the agency of the specially designed clamp 51. As particularly disclosed in Figs. 3, 5 and 6, this clamp comprises an elongated body 52 provided with a longitudinal aperture 53 of sufficient uniform width to permit a sliding fit for the guide-rod. The rear end 54 of the aperture is preferably made circular with a bead 55 at its lower circumference. The semi-circular top part of the aperture is horizontal, whereas the bottom part is made forwardly declining so that the front end 56 of the aperture will assume the elongated form shown in Fig. 6. Centrally positioned and longitudinally spaced on the clamp are the set-screw 57 and the clamping thumb-screw 58, the purpose of which is explained herebelow. The front end of the clamp is also provided near the bottom with the outwardly directed prongs 59.

The clamping of the carborundum slab is done as follows: The slab 50 is first placed symmetrically under the guide-rod 47 with its forward end bearing against the prongs 49. The clamp 51 is now slid forward on the guide-rod until the prongs 59 barely touch the rear end of the carborundum slab. The set-screw 57 is now forced somewhat into the guide-rod and the slab is finally solidly fixed between both sets of prongs by forcing the thumbscrew downward. This will cause the forward end of the clamp to describe an arcuate movement upwardly, with the set-screw 57 as a center or fulcrum, thereby forcing prongs 59 into the carborundum slab and holding it rigidly in place.

To remove the slab, it is not necessary to unloosen the set-screw 57, it suffices to part-

ly unscrew the thumb-screw 58, thereby allowing the forward end of the clamp to drop, thus separating the prongs from the carborundum slab.

The preceding detailed description of my invention, taken in connection with the drawings will make the method of using the machine easily understood; it is as follows: The tool to be sharpened, for instance the adjustable reamer 11, is placed and rather firmly held between the centers 6 and 9; the head and tail-stocks having first been suitably clamped on the table 1 to bring the middle of the cutting part of the reamer substantially in line with the center of the standard 17. The carborundum slab is then adjusted to set level upon the blade 11^a of the reamer and the end of the push-blade is brought to bear against the near side of the blade 11^a; see Fig. 10. The rest-bar is now clamped in the adjustable rest 28 and the exact amount of clearance or relief is obtained by forcing the push-blade forward by means of the feed-screw 21. The reamer is now firmly clamped between the centers 6 and 9 and the sharpening of the blade 11^a is obtained by manually passing the carborundum slab back and forth over it. Fig. 11 shows in dot and dash lines how, by moving forward the push-blade, the top of blade 11^a is ground off at the back to produce the desired clearance. Fig. 12 shows the shape of the finished blade and the arrow indicating the operating direction of the reamer. The same operations are repeated for each blade of the reamer.

As will be understood, as suggested herein there may be slight changes made in the construction and arrangement of the details of my invention without departing from the field and scope of the same, and I intend to include all such variations as fall within the scope of the appended claims, in this application in which the preferred form only of my invention is disclosed. It will also be noted that in said claims mention is made only, for the sake of brevity, of the use of this machine for sharpening reamers; but it is understood that these claims are to be read as including milling-cutters, all suitable types of reamers and similar tools.

What I claim is:

1. In a sharpening machine of the character described, the combination of axially aligned center supports for supporting the tool to be sharpened; manually operated reciprocating sharpening means; a guide rod therefor; adjustable means for securing said sharpening means to said guide-rod; a rest-bar disposed rectangularly to the axis of said center supports having a horizontal and a vertical portion; a horizontally rotatable guide for said guide-rod mounted upon the vertical portion of said rest-bar; a vertically adjustable rest for said rest-bar; a flexible push-

- blade secured and positioned at the end of the horizontal portion of said rest-bar and means for moving said rest-bar at right angles to the axis of said center supports for 5 imparting to the tool to be sharpened a fractional part of a revolution required for producing the desired relief on the cutting edge of said tool.
2. In a sharpening machine of the character described, the combination of axially aligned center supports for supporting the tool to be sharpened; manually operated reciprocating sharpening means; a guide-rod therefor; clamping means slidably mounted 10 upon said guide-rod for securing said sharpening means thereto; means for releasing said sharpening means from said guide-rod without longitudinally displacing said clamping means; a rest-bar disposed rectangularly 15 to the axis of said center supports having a horizontal and a vertical portion; a horizontally rotatable guide-rod mounted upon the vertical portion of said rest-bar; a vertically adjustable rest for said rest-bar; a flexible push-blade secured and positioned at 20 the end of the horizontal portion of said rest-bar and means for moving said rest-bar at right angles to the axis of said center supports for imparting to the tool to be 25 sharpened a fractional part of a revolution required for producing the desired relief on the cutting edges of said tool.
3. In a sharpening machine of the character described, the combination of axially aligned center supports for supporting the tool to be sharpened; manually operated re- 30
- ciprocating sharpening means; a guide-rod therefor; clamping means slidably mounted upon said guide-rod for securing said sharpening means thereto; means for releasing 35 said sharpening means from said guide-rod without longitudinally displacing said clamping means; the latter comprising a sleeve-member having an aperture of uniform width and level at the top but of varying depth increasing towards the sharpening means clamped thereby, said aperture being engaged by said guide-rod; a set-screw positioned above and adjacent the small end of said aperture in said clamping means for 40 securing the same on said guide-rod against longitudinal displacement, and another screw positioned above and adjacent the larger end of said aperture for arcuately moving said clamping means around said 45 set-screw as a fulcrum; a rest-bar disposed rectangularly to the axis of said center supports having a horizontal and a vertical portion; a horizontally rotatable guide for said guide-rod mounted upon the vertical portion of said rest-bar; a vertically adjustable rest for said rest-bar; a flexible push-blade secured and positioned at the end of the horizontal portion of said rest-bar, and means for moving said rest-bar at right angles to 50 the axis of said center supports for imparting to the tool to be sharpened a fractional part of a revolution required for producing the desired relief on the cutting edges of said tool. 55
- 70

In testimony whereof I affix my signature.

THOMAS C. DONAHUE.
